ELECTRIC SHAVER

Robert O. Ernest, Oak Park, Ill., assignor to Sunbeam Corporation, Chicago, Ill., a corporation of Illinois

Application September 13, 1955, Serial No. 37,908

Term of patent 14 years

(Cl. D22—3)

Fig. 1.

Fig. 2.

Fig. 3.

Fig. 1 is a front elevational view of an electric shaver, showing my new design, the opposite face thereof presenting a similar appearance;

Fig. 2 is a side elevational view of the electric shaver of Fig. 1; and

Fig. 3 is a top plan view of the electric shaver of Fig. 1.

I claim:

The ornamental design for an electric shaver, substantially as shown and described.
